UNITED STATES PATENT OFFICE.

JOHN BATES, OF TURLOCK, CALIFORNIA.

DITCH-GUARD.

1,153,186.

Specification of Letters Patent. Patented Sept. 14, 1915.

Application filed October 31, 1913. Serial No. 798,520.

To all whom it may concern:

Be it known that I, JOHN BATES, a citizen of the United States, residing at Turlock, in the county of Stanislaus and State 5 of California, have invented certain new and useful Improvements in Ditch-Guards, of which the following is a specification.

This invention relates to a guard which is intended to be placed at the mouth of a 10 canal forming a part of an irrigating system.

One of the objects of the invention is to so construct the guard that it will prevent fish from entering the irrigating system, but at the same time not interfere with water 15 entering the inlet canal.

Another object of the invention is to so construct the guard that it will prevent drift from collecting at the mouth of the canal.

Another object of the invention is to so 20 construct the guard that it may be put in place no matter whether the two sides of the canal terminate in alinement or out of alinement.

Another object of the invention is to so 25 construct the guard that its frame may be formed from a single sheet of material.

This invention is illustrated in the accompanying drawings wherein—

Figure 1 is a plan view showing the guard 30 in place with the sides of the canal terminating in alinement; Fig. 2 is a view similar to Fig. 1 showing the guard in place with the two sides of the canal terminating out of alinement. Fig. 3 is a fragmentary 35 plan view of the guard; Fig. 4 is a view in elevation looking at the outer face of the guard; Fig. 5 is a view in elevation looking at the inner face of the guard.

Referring to the drawings it will be seen 40 that this device is to be placed at the outer end of the inlet canal 10 which leads from the river 11 from which the water for the irrigating system is drawn. The ends of the guard are secured to the post 12 and since 45 the guard is to a certain extent flexible, it may be readily connected with the post no matter whether these posts are in alinement as shown in Fig. 1 or out of alinement as shown in Fig. 2.

The guard is formed from an elongated 50 strip of material 13 which is preferably metal or some other similar material. This strip is to be of such width that it will extend to the bottom of the inlet canal, and also if desired extend as far above the level 55 of the water as the person constructing the

canal may wish. This strip 13 has tongues 14 struck therefrom and is bent transversely along the lines of the side edges of the openings formed by these tongues 14 so that the tongues will extend outwardly at an acute angle to the openings as shown in Fig. 3. These tongues 14 will extend out into the river 11 with their free edges extending down stream so that logs and other drift floating down the river will be guided away 65 from the inlet canal, and thus prevented from lodging against the guard. It is also to be noted that by having the strip crimped, as shown, the guard will be resilient and will thus be able to stand a blow received 70 when a large log strikes the guard. It will therefore have a spring action to prevent its being broken or drawn loose from the post 12. It will also be noted that this construction will permit the strip to be stretched 75 slightly in case the strip is cut a little too narrow and that it may also be compressed in case it is cut a little too long for the width of the canal.

The prime object of this construction is to cause the tongues 14 to guide drift away from the mouth of the canal and thus prevent the drift from accumulating at the guard. A strip of wire mesh 15 is placed 80 against the inner face of the strip 13 and is secured in place by wires 16 which extend along the inner face of the wire and are then passed through the wire so that their end portions may be passed through the upper and lower ends of the openings formed 85 by the tongues 14 and may be bent about the upper and lower edge portions of the strip 13. This manner of securing the wire is very clearly shown in Figs. 4 and 5. This 90 wire serves the purpose of preventing fish from entering the canal 10 through the openings formed by the tongues 14.

The manner of using this guard will be very clearly understood from an inspection 100 of Figs. 1 and 2. The guard which may be made in long strips and wound upon suitable reels is cut the proper length and these pieces which are cut from the roll are then secured at their ends to the posts 12 by any 105 suitable means such as nails or the like. As already explained, the strip must be cut full length so that when in place the guard will be bowed outwardly as shown in Figs. 1 and 2 and extend into the river 11, thus causing 110 the drift to be guided out into the center of the river where the current is strongest. A

guard constructed in this manner will not be liable to be quickly destroyed or the wire dragged loose since the wire is placed upon the inner face of the strip and therefore can not be caught by the drift. The spring action already explained will prevent large logs from striking the guard and tearing it loose from the post.

What is claimed is:

- 10 1. A ditch guard comprising a strip of material having tongues struck therefrom and being crimped transversely in alignment with the openings formed by said tongues to cause the tongues to extend outwardly at an angle to said openings, and screening secured to the inner face of said strip and extending across said openings.
- 15 2. A ditch guard formed from a strip of resilient material having tongues struck

therefrom and being crimped transversely to cause said tongues to extend outwardly at an angle to the openings formed by said tongues.

3. A ditch guard formed from a strip of material crimped transversely to provide alternate faces extending substantially parallel, one set of parallel faces being provided with openings, and strips extending outwardly from the second set of parallel faces partially across the openings formed in the first mentioned set of parallel faces.

In testimony whereof I affix my signature in presence of two witnesses.

JOHN BATES.
